(57) **CLAIM**

The ornamental design for the firing pin for a firearm, as shown and described.

DESCRIPTION

FIG. 1 is a perspective view of the firing pin for a firearm; FIG. 2 is a front view of the firing pin of FIG. 1; FIG. 3 is a back of the firing pin of FIG. 1; FIG. 4 is a left side view of the firing pin of FIG. 1; FIG. 5 is a right side view of the firing pin of FIG. 1; FIG. 6 is a top view of the firing pin of FIG. 1; FIG. 7 is a bottom view of the firing pin of FIG. 1; and, FIG. 8 is a left side view of the firing pin of FIG. 1 as mounted in a firearm.

The broken line showing of FIG. 8 is for the purpose of illustrating the firearm that houses the firing pin, and forms no part of the claimed design.
